UNITED STATES PATENT OFFICE

160,859

DOOR KNOCKER

Samuel K. Harker, West Lafayette, Ind.

Application August 2, 1949, Serial No. 4,254

Term of patent 14 years

(Cl. D10—7)

To all whom it may concern:

Be it known that I, Samuel K. Harker, a citizen of the United States and a resident of West Lafayette, county of Tippecanoe, and State of Indiana, have invented a new, original, and ornamental Design for a Door Knocker, of which the following is a specification, reference being had to the accompanying drawing, forming part thereof.

In the drawing:

Fig. 1 is a front elevational view of a door knocker, showing my new design. Fig. 2 is a side elevation of the door knocker shown in Fig. 1, both sides being substantially alike and the knocker being substantially symmetrical.

I claim:

The ornamental design for a door knocker, as shown and described.

SAMUEL K. HARKER.
